POLISHING DISK

Philip W. Dempsey, Pittsburgh, Pa., assignor to
The Westinghouse Air Brake Company, Wil-
merding, Pa., a corporation of Pennsylvania

Application April 6, 1936, Serial No. 72,853

6 Claims. (Cl. 51—197)

My invention relates to flexible polishing pads or backing disks for sheets of abrasive material, and method of making the same.

It has been well known to provide flexible disks 5 of felt and like material as a backing structure for sheets of abrasive material for polishing flat surfaces.

Many such backing disks are not sufficiently solid or rugged to withstand the strains placed 10 upon them when run at high speed, and such disks when operated at high speed tear out at the bolt holes through which they are attached to the flanged shaft on which they are mounted. Also the felt disks are expensive to manufacture.

15 An object of my invention is to provide flexible backing disks for abrasive sheets and a method of making the same.

Another object of my invention is the provision of backing disks of the character described 20 that are inexpensive to manufacture and are sufficiently rugged and firm to be capable of use at high speed.

A further object of my invention is the provision of a disk of the character described formed 25 of rubber reinforced with fabric and metal.

Other objects and advantages of my invention will be apparent from the following description of one preferred embodiment of a disk constructed in accordance with my invention, reference 30 being had to the accompanying drawings, in which

Fig. 1 is a face view of a finished flexible disk constructed in accordance with my invention with a portion thereof broken away.

35 Fig. 2 is a sectional view taken from the line 2—2 of Fig. 1.

Fig. 3 is a sectional view taken from the line 3—3 of Fig. 1.

40 Fig. 4 is an enlarged sectional view of a portion of the disk taken along the line 2—2 in Fig. 1.

Fig. 5 is a sectional view along the line 5—5 in Fig. 6, showing the built-up blank before being placed in the mold to be vulcanized.

45 Fig. 6 is an exploded view showing the several layers of material from which the flange is constructed, separated from one another,

Fig. 7 is a perspective view of a roll of rubberized fabric material for insertion in openings 50 provided therefor in the blank, and

Fig. 8 is a sectional view of a blank placed within a mold.

Referring to the drawings, and more particularly to Figs. 1 and 2 thereof, I provide a disk 55 for the purpose intended that overcomes the

above objections of prior flexible disks, having a body portion 1 of vulcanized rubber reinforced with fabric 2, having a metal disk core 3, that is provided with holes 4 extending through the metal center and body portion for accommodat- 5 ing bolts 5 by means of which the disk is attached to a suitable flange 6 of a driving shaft 7. A retaining member 8, shown broken away in Fig. 2, is also provided centrally of the disk and screw-threadedly attached to the shaft 7. 10

Holes 10 are also provided in the metal disk 3 and are centered between two bolt holes 4 to accommodate rolls 9 (Fig. 7) of reinforcing ma- 15 terial that extend through the metal core and body portion of the disk.

The backing disk illustrated in Figs. 1 and 2, is made by the following process, the dimensions given being illustrative merely of one specific embodiment.

Rubber compound is first rolled into sheets 20 having the desired thickness of stock, for example, (1) stock having a thickness of .095 to .100"; (2) stock having a thickness of .140" to .145"; and (3) stock having a thickness of .155" to .160". 25

Rubber compound is also rolled or "frictioned" onto a sheet of wide mesh cotton fabric, such as 24 oz. hose duck, so that the layers of rubber on the opposite sides of the fabric are united by the rubber pressed into the interstices between the 30 strands of the fabric. This frictioning is done in such a way as to cover the fabric with as heavy a coat of rubber on both sides of the fabric as possible, the material being rolled until the thickness of the rubber compound coating of 35 the fabric is within the specified limits. The materials thus prepared have a tacky surface, so that contacting surfaces adhere to one another as they are assembled, so as to form a blank 40 that may be placed in a heated mold and pressed and curved into a finished disc.

To form the composite blank illustrated in Fig. 5 of say 9 inch external diameter, two circular blanks 11 and 12 in Fig. 6 are punched from the frictioned duck having 9 inch external 45 diameters and, say, 2 $\frac{1}{2}$ inch internal diameters; four blanks, 13, 14, 15 and 16, are punched from the frictioned duck having 7 inch external and 2 $\frac{1}{2}$ inch internal diameters. Two blanks 17 and 18 are punched from the sheet of raw rubber 50 compound stock that has been calendered to a thickness of from .095 inch to .100 inch, the blanks having an external diameter of 9 inches, and an internal diameter of 7 inches. One blank 19 is punched from the stock that has been cal- 55

endered to a thickness of .140 inch to .145 inch, the blank having an external diameter of 9 inches and an internal diameter of $2\frac{1}{8}$ inches. One blank 21 is punched from the stock which has been calendered to a thickness of .155 inch to .160 inch, the blank having an outside diameter of 9 inches and an inside diameter of $2\frac{1}{8}$ inches.

In building up a composite blank, as shown in Fig. 5, the 9 inch external diameter blank 11, and the 7 inch external diameter blanks 13 and 14 of frictioned duck are placed together and rolled to remove any trapped air. Six holes are punched, centered around the central opening 15 to line up with the bolt holes 4 in the metal ring 3 and of sufficient diameter to accommodate the heads of the bolts as shown in Figs. 2 and 5. A like number of larger holes are equally spaced between the bolt holes to line up with the holes 10 in the metallic plate 3 to accommodate the reinforcing rolls of fabric material 9 when in final position.

The remaining 9 inch blank 12 and the two 7 inch blanks 15 and 16 of frictioned duck are now placed together and similarly rolled to remove any trapped air and are punched with holes corresponding to the holes 4 and 10 in the metal plate 3, the bolt holes in this case having a diameter sufficient only to accommodate the shaft of the bolts 5 as shown in Figs. 2 and 5.

The metal disk 3 is then cleaned up by washing in benzol or similar cleaning liquid and given a coating of rubber cement. When the solvent in the rubber cement has evaporated the disk is then placed on the blank consisting of the three layers 12, 15 and 16, with the holes properly lined up with those punched in the fabric. The blank comprising the three layers of fabric 13, 14 and 11 is then placed on the disk, the several layers being in the order shown in Fig. 6. The blank 17 of rubber compound stock is then placed in position with the inner diameter thereof matching the outer diameter of the blanks 13 and 14, and in like manner the blank 18 is positioned so that its inner diameter matches the outer diameter of the blanks 15 and 16. The blanks 19 and 21 of rubber compound stock are then placed in position after holes corresponding to those in blanks 11 and 12, respectively, have been punched therein.

Six pieces or strips of material from the frictioned fabric are now cut, of such dimensions as to form rolls of sufficient diameter to fill the holes 10, and of sufficient length to correspond with the width of the assembled composite blank as illustrated in Fig. 5. These rolls are placed in the openings 10 in the composite blank, and the assembled composite blank inverted and placed in a hot mold comprising a base section 20 21, as shown in Fig. 8, from which members 22 extend into the bolt holes. The mold cover section 23 is next placed in position, and the mold then placed in a proper press and allowed to vulcanize for twenty-five or thirty minutes at approximately fifty pounds steam pressure, at the end of which time the disk is removed from the mold to prevent an over cure. The edges of the disk and the bolt holes are trimmed and the disk is ready for use.

70 The numerals used in Figs. 5 and 6 to identify

the separate layers of raw material are applied to Figs. 3 and 4, to show the location of material in the finished disk, it being understood, however, that, upon vulcanizing, the individual layers of material lose their identity and become 5 a composite whole.

It will be understood by those skilled in the art, that many modifications in the above described embodiment of my invention may be made without departing from the spirit of my invention, and I do not wish to be limited, otherwise than by the scope of the appended claims.

Having now described my invention, what I claim as new and desire to secure by Letters Patent, is:

1. A flexible backing disk pad for abrasive sheets comprising a central metallic core disk to the opposite sides of which are formed a body portion consisting of vulcanized rubber reinforced with fabric material, said body portion and metallic core disk having registered transverse openings therethrough in which are positioned 20 rolled fabric reinforcing plugs.

2. A resilient backing disk for abrasive sheets comprising a central rigid core disk about which is formed a body portion consisting of layers of rubberized fabric and layers of rubber composition, said body portion and rigid core disk having registered transverse openings therethrough through which extend plugs of rolled rubberized 30 fabric.

3. A resilient backing disk for abrasive sheets comprising a central rigid core disk about which is formed a body portion consisting of layers of rubberized fabric on opposite sides of and adjacent said core disk, and layers of rubber composition adjacent said fabric, said body portion and rigid core disk having registered transverse openings therethrough through which extend 35 plugs of rolled rubberized fabric. 40

4. A resilient backing disk for abrasive sheets comprising a central rigid core about which is formed a body portion consisting of layers of rubberized fabric on opposite sides of and adjacent said core and layers of rubber composition 45 adjacent said fabric, the disk being provided with holes extending through the core and body portion through which may extend suitable supporting means for attaching the disk to a driving member.

5. In a resilient backing disk for abrasive sheets comprising a central rigid core disk about which is formed a body portion consisting of layers of rubberized fabric and layers of rubber composition, said body portion and core disk having registered transverse openings through which extend 55 plugs of rolled rubberized fabric, said disk and body portion being also provided with holes extending therethrough through which may extend suitable supporting means for attaching the 60 disk to a driving member.

6. In a device of the class described, a metallic reinforcing plate, rubberized fabric disks of substantially the diameter of the completed article at each face of said reinforcing plate, other rubberized fabric disks of smaller diameter than the completed article at the faces of the first named fabric disks, and rubber composition overlying said layers of fabric.

PHILIP W. DEMPSEY. 70
